TOY DERRICK

Harold B. Boone, Arcadia, Kans.

Application September 8, 1950, Serial No. 183,873

3 Claims. (Cl. 212—55)

1

This invention relates to toys, and more particularly to a miniature derrick or bucket hoist.

A main object of the invention is to provide a novel and improved toy derrick or bucket hoist, which is very simple in construction, which is easy to operate, and which is very useful in teaching children proper coordination of hands and feet.

A further object of the invention is to provide an improved toy derrick or bucket hoist which is relatively inexpensive to manufacture, which is sturdy in construction, which is readily movable from one location to another, and which provides useful exercise as well as entertainment for children.

Further objects and advantages of the invention will become apparent from the following description and claims, and from the accompanying drawings, wherein:

Figure 1 is a side elevational view of an improved toy derrick constructed in accordance with the present invention;

Figure 2 is a rear end elevational view of the toy derrick of Figure 1;

Figure 3 is a top plan view of the toy derrick of Figures 1 and 2;

Figure 4 is an enlarged top plan detail view of the pivoted cable brake member employed on the upstanding post element of the derrick of Figure 1;

Figure 4-a is a side elevational detail view of the brake member illustrated in Figure 4;

Figure 5 is an enlarged top plan detail view, partly in cross-section, of the inner section of the extensible boom employed on the toy derrick of Figure 1;

Figure 6 is a detail plan view of the outer section of the extensible boom employed in the toy derrick of Figure 1;

Figure 7 is a diagrammatic view illustrating the cable connections employed for extending and retracting the telescopic boom of the toy derrick of Figure 1;

Figure 8 is a longitudinal, vertical, cross-sectional view taken through the telescopic boom of the toy derrick of Figure 1.

Referring to the drawings, 11 generally designates the frame of the boom, said frame comprising the upstanding rear bar elements 12, 13, and upstanding forward bar elements 14, the respective rear and forward bar elements being connected at their top ends by longitudinal frame elements 15 and being connected at their lower portions by a metal plate member 16. Secured to the forward ends of the longitudinal members 15, 15 is a transverse, horizontal plate member

2

17, and rigidly connected to the forward corners of the plate member 17 are depending bar members 18. Extending rotatably through the lower portions of the bar members 18 is a transverse axle 19 carrying the respective supporting wheels 20, 20. As shown in Figure 1, the frame portion 11 is normally supported on the legs 12, 13 and 14, but may be transported by elevating the rear portion of the frame 11 whereby the forward portion will be supported on the wheels 20. This enables the frame to be readily moved from place to place.

Designated at 21 is a vertical post member or upstanding post which extends rotatably through plate member 17 and is supported on the forward end portion of the plate member 16 for rotary movement about a vertical axis or a bearing 22. A boom 24 is arranged longitudinally of the frame 11 and forwardly of the post 21 and embodies a first section 25 having one end connected to the post 21 intermediate its ends for up-and-down movement about a horizontal axis or pivot 23, and a second section 26 having one end receiving the other end of the section 25 and connected to the section 25 for extensible and contractile movement. The section 26 is provided adjacent its other end with an eye 27 to which is secured one end of a cable 28. Cable 28 passes over a pulley 29 rotatably mounted in the upper portion of the vertical post member 21, the end of said cable being connected to an eye 30 secured to the top portion of the post member. Designated at 31 is a weight suspended from a pulley 32 engaged on the cable 28 adjacent the post member 21. Designated at 33 is a latch member or locking lever pivotally mounted on a transverse pin 34 secured in the top portion of the post member 21, said latch member having a serrated end 35 and being provided at its opposite end with a weight 36, the serrated end 35 being located inwardly adjacent the cable 28 and the weight 36 biasing said serrated end into locking engagement with the cable.

As viewed in Figure 1, the weight 36 biases the pivoted latch member 33 in a clockwise direction, whereby the end 35 is urged against the depending portion of the cable 28. Engagement of the serrated end 35 with the cable 28 restrains the boom 24 against clockwise rotation, as viewed in Figure 1, whereby said boom may be releasably locked in an elevated position. The locking lever 33 may be moved counterclockwise to a released position to release cable 28 by means of a release rod 37 extending upwardly through the post member 21 and engaging the lower surface of the lever 33 subadjacent the weight portion 36. The

lower end of rod 37 is pivotally connected to one arm of a bent lever 38 pivoted to the frame 11, the end of the other arm of said lever being connected by a rod 39 to the arm 40 of a crankshaft 41 rotatably mounted on an upstanding bracket 42 carried by the frame 11. The lower ends of the bar members 12 and 13 are connected by a transverse bar member 43 to which the bracket 42 is secured. A similar transverse bar member 44 connects the lower ends of the support elements 14.

The crankshaft 41 is provided with a foot actuatable means or handle 45 which is adapted to be operated by foot pressure. When the crankshaft 41 is rotated counterclockwise, as viewed in Figure 1, the rod 39 rotates the bent lever 38 clockwise, causing the release rod 37 to be moved upwardly, whereby the lever 33 is rotated counterclockwise, allowing the cable 28 to be released.

Designated at 46 is an upstanding bucket which is arranged adjacent the other end of the second section 26 and has the upper end dependingly supported from the other end of the section 26. Specifically, the bucket 46 is detachably connected to a pulley 47 supported on a cable 48. One end of the cable is connected to the other end of the section 26 of the boom 24, the cable passing over a pulley 48a rotatably mounted in the end of the section 26, said cable 48 extending over a pulley 49 rotatably mounted in the top end of the post member 21, and thence beneath a pulley 50 carried on the upper portion of the frame 11 to a reel 51 journaled transversely between the rear support bars 12 and 13. Reel 51 is provided with a hand actuatable means or crank handle shown at 52. The bottom end of the bucket 46 is connected by a short length of cable 53 to the outer section 26 of the boom 24, and is further connected by a cable 54 which passes over a pulley 55 carried by the section 26 of the boom and over another pulley 56 carried on a rearwardly extending arm 57 secured to the inner end of the section 26. A weight 58 is slidably mounted on the cable 54 between the pulley 55 and the bottom end of the bucket.

As shown in Figure 8, a transverse pin 59 extends through the inner end portion of the section 26 and passes through respective longitudinal slots 60, 60 formed in the inner boom section 25. A pulley 61 is provided in the outer end portion of the section 25. Designated at 62 is a cable connected at one end to the transverse pin 59 and which extends over the pulley 61 and thence back through the section 25 over a pulley 63 mounted on the pivot pin 23. Another cable 64 is connected to the transverse pin 59 and also extends over the pulley 63. The cables 64 and 62 extend downwardly through the lower portion of the post member 21 and around pulleys 65, 66 carried by the frame 11. The ends of the cables 64 and 62 are wound on a transverse shaft 67 journaled in the vertical support members 12 and 13. Shaft 67 is provided with a crank handle 68 and has rigidly secured thereon a ratchet wheel 69. Engaging the ratchet wheel 69 is a dog 70 which is biased in any suitable manner into locking engagement with the ratchet wheel to lock the boom sections in extended relation until the dog member is withdrawn from engagement with the ratchet wheel. Designated at 71 is a foot actuatable means or crank adapted to be foot operated and which is rotatably supported on a bracket 72 secured to the transverse bar member 43. Member 71 is connected to the dog 70 by a link 73, whereby foot pressure on the

member 71 causes the dog 70 to be withdrawn from engagement with respect to the ratchet wheel 69. It will be readily apparent that by rotating the shaft 67 by means of the crank 68, the boom may be extended, and that the boom may be collapsed by disengaging the dog member 70 from the ratchet wheel 69, whereby the outer section 26 of the boom will telescope over the inner section 25 by gravity, assuming that the boom is in an elevated position. If the boom is in a depressed position, it may be collapsed by merely reversing the rotation of the crank 68, at the same time holding the dog 70 disengaged from the ratchet wheel 69 by means of the foot-operated member 71.

Mounted on the lower portion of the post member 21 is a pulley 73a around which extends a cable 74. Cable 74 is wound on a transverse shaft 75 journaled in the upper portions of the vertical bar members 12 and 13, said shaft being provided with a hand actuatable means or crank handle 76. Rotation of the crank handle 76 in one direction causes the post member 21 to swivel in one direction, and rotation of the crank handle 76 in the opposite direction similarly reverses the direction of swiveling of the post member 21.

A typical method of operation of the above-described toy device is as follows:

The operator places both feet on the pedals 71 and 45, places his right hand on the crank 52 and his left hand on the crank 68. It will be understood that the boom 24 is in its lowered, collapsed position at this time. The operator then rotates crank 68 which causes the boom to be extended and at the same time causes the bucket 46 to dig into sand or loose dirt subadjacent to the boom. After the bucket has been filled, the operator rotates the crank 52 to elevate the boom, at the same time releasing both of the foot-operated members 71 and 45. Dog 70 will engage the ratchet wheel 69, holding the boom in extended position. The boom is elevated to the desired height by means of the hand crank 52, the locking lever 33 engaging the cable 28 and supporting the boom at its desired elevation. While raising the boom with his right hand, the operator may swing the boom either to the right or left by rotating the crank 76 with his left hand. The boom may be swung substantially a complete revolution. To discharge the load, the operator merely releases the crank 52, allowing the cable 48 to unwind from the reel 51, whereby the cable 53 causes the bucket 46 to be inverted as it descends. The operator may then raise the bucket by rotating the crank 52, at the same time using the crank 76 to bring the boom back to the loading position. The operator may then engage his left foot with the crank 71, allowing the boom to return to its collapsed position by gravity, and the boom may then be lowered to its starting position by exerting foot pressure on the crank 45, which releases the cable 28. The device is then ready to repeat the above-described operation.

While a specific embodiment of an improved toy hoist device has been disclosed in the foregoing description, it will be understood that various modifications within the spirit of the invention may occur to those skilled in the art. Therefore, it is intended that no limitations be placed on the invention except as defined by the scope of the appended claims.

What is claimed is:

1. A toy derrick comprising a frame, an upstanding post supported on said frame for rotary

movement in opposite directions about a vertical axis, a boom arranged longitudinally of said frame and forwardly of said post, said boom embodying a first section having one end connected to said post intermediate its ends for up-and-down movement about a horizontal axis and a second section having one end received in the other end of said first section and connected to said first section for extensile and contractile movement, an upstanding bucket arranged adjacent the other end of said second section and having the upper end dependingly supported from the other end of said second section, hand actuatable means operatively connected to the other end of said second section for effecting the up-and-down movement of said first section, a foot actuatable means operatively connected to said first and second sections for effecting the extensile and contractile movement of said second section, flexible means connecting the lower end of said bucket to the horizontal axis of said first section, and a second hand actuatable means operatively connected to said post for effecting the rotary movement of the post.

2. A toy derrick comprising a frame, an upstanding post supported on said frame for rotary movement in opposite directions about a vertical axis, a boom arranged longitudinally of said frame and forwardly of said post, said boom embodying a first section having one end connected to said post intermediate its ends for up-and-down movement about a horizontal axis, and a second section having one end receiving the other end of said first section and connected to said first section for extensile and contractile movement, an upstanding bucket arranged adjacent the other end of said second section and having the upper end dependingly supported from the other end of said second section, a hand actuatable means operatively connected to the other end of said second section for effecting the up-and-down movement of said first section, a foot actuatable means operatively connected to said first and second sections for effecting the extensile and contractile movement of said second section, a second foot actuatable means engageable with said first-named hand actuatable means for holding said boom in its up-movement position, flexible means connecting the lower end of said bucket to the horizontal axis of said first section, and a second hand actuatable means operatively connected to said post for effecting the rotary movement of the post.

40

45

to the horizontal axis of said first section, and a second actuatable means operatively connected to said post for effecting the rotary movement of the post.

5. A toy derrick comprising a frame, an upstanding post supported on said frame for rotary movement in opposite directions about a vertical axis, a boom arranged longitudinally of said frame and forwardly of said post, said boom embodying a first section having one end connected to said post intermediate its ends for up-and-down movement about a horizontal axis and a second section having one end receiving the other end of said first section and connected to said first section for extensile and contractile movement, an upstanding bucket arranged adjacent the other end of said second section and having the upper end dependingly supported from the other end of said second section, a hand actuatable means operatively connected to the other end of said second section for effecting the up-and-down movement of said first section, a foot actuatable means operatively connected to said first and second sections for effecting the extensile and contractile movement of said second section, a locking lever pivotally supported on said post adjacent its upper end and engageable with said first-named hand actuatable means for holding said boom in its up-movement position, a second foot actuatable means operatively connected to said locking lever for releasing said lever from engagement with said first-named hand actuatable means, flexible means connecting the lower end of said bucket to the horizontal axis of said first section, and a second hand actuatable means operatively connected to said post for effecting the rotary movement of the post.
